UNITED STATES PATENT OFFICE

113,832

DESIGN FOR A DIVAN

Thomas M. Cross, Southgate, Calif., assignor to David J. Saltman, Southgate, Calif.

Application January 28, 1939, Serial No. 82,645

Term of patent 3½ years

To all whom it may concern:

Be it known that I, Thomas M. Cross, a citizen of the United States, residing at Southgate, in the county of Los Angeles, State of California, have invented a new, original, and ornamental Design for a Divan, of which the following is a specification, reference being had to the accompanying drawings, forming part thereof.

Fig. 1 is a view in front elevation of the divan embodying my new design; Fig. 2 is a rear view in elevation of the same; Fig. 3 is a view in end elevation of the divan; Fig. 4 is a top plan view of the divan embodying the design; and Fig. 5 is a transverse vertical sectional view through the divan embodying the design.

I claim:

The ornamental design for a divan, as shown.
THOMAS M. CROSS.
